UNITED STATES PATENT OFFICE.

WALTER EDWIN TRENT, OF WASHINGTON, DISTRICT OF COLUMBIA.

PROCESS OF MANUFACTURING GAS.

Application filed August 31, 1922. Serial No. 585,385.

To all whom it may concern:

Be it known that I, WALTER EDWIN TRENT, a citizen of the United States, residing at Washington, in the District of Columbia, have invented certain new and useful Improvements in Processes of Manufacturing Gas, of which the following is a specification.

The invention relates to a process for manufacturing combustible gases.

It is an object of the invention to provide a process for manufacturing evolved water gas wherein a bed of coke and substantially all of the hydrocarbon content of the fuel employed is used as a coal gas for enriching the water gas, thereby eliminating or materially reducing the quantity of hydrocarbon oils now generally used in the carburation of blue water gas made with substantially non-volatile coals. The production of the enriched water gas by my process is accomplished by first subjecting fresh carbonaceous fuel to the heat of generated water gas to gasify the volatiles thereof forming a combined coal and water gas and a coke residue which is thereafter used as a water gas making fuel.

In the preferred practice of my invention I employ a series of fuel containers successively used for carburetting and gas making purposes. In operation a container having a supply of coke is subjected to the usual alternate air and steam run such as now universally practiced in the manufacture of water gas. During an air run the fuel is discharged to a superheater and then passes to a stack, while during a steam run the decomposed steam or water gas is introduced and passes through a communicating container having a mass of fresh fuel with a hydrocarbon content to cause a vaporization of the volatiles therein which mix with and enrich the hot water gas. The alternate air and steam runs are continued with respect to the carbonized charge until the volatile content of the fresh charge in the communicating container has been fully gasified, then this container with its carbonized residue is employed for the generation of water gas by subjecting the residue to the usual air and steam runs. The coke in the previous water gas making container is discharged and a supply of fresh fuel substituted in lieu thereof so that this container now becomes a carburetting container for enriching the blue water gas introduced thereto.

The alternate use of the containers first as a water gas generator, then as a carburetor is continued throughout the operation of the process, thereby permitting the fuel that is used to be properly robbed of its volatiles for enriching the water gas with coal gases before said fuel as a coke mass is subjected to the action of steam for the production of the usual blue water gas.

As a fuel for the production of the combined coal and water gas various carbon and hydrocarbon substances may be employed. I preferably, however, use a composite fuel of a plastic consistency composed of finely comminuted coal and hydrocarbon oil with or without a small content of water. These substances are usually in such definite proportions as to form a plastic mass through which there can be formed a series of vertical openings to be used as gas passageways. The fuel herein described may be produced in the manner disclosed in my Patent No. 1,420,164.

In the accompanying drawings I have shown one embodiment of this invention capable of supporting the process, in which Figure 1 illustrates a top plan view.

Figure 2 is a side elevation; and,

Figure 3 is a vertical sectional view of one of the receptacles.

Referring now more particularly to the drawings wherein like reference characters indicate corresponding parts, the numerals 1 and 2 designate a pair of containers, two being shown in the present disclosure, although it will be understood that any number may be used. These containers are each mounted upon suitable supports, the container 1 being mounted upon a support 3 while the container 2 is mounted upon a support 4. Inasmuch as the construction of both of the supports is identical, a description of one will suffice for both. Each support is preferably composed of concrete or the like having upstanding walls 5 and a partition 6 forming therein the chambers 7 and 8. The upstanding portions 5 of the supports constitute seats upon which the containers 1 and 2 are mounted. These containers are of a similar construction so that a description of one will do for both of them. Each container is preferably formed with a metallic wall having an upper flange 6' adapted to receive a flange 7' on the removable tops of the container and to form therebetween a water seal. The

lower portion of the wall of each container is likewise provided with a flange 8' seated within a U-shaped member 9 mounted upon the upstanding portions 5 of each of the supports 3 and 4 so as to provide a water seal at the lower part of the container. Each container is also formed with the bottom 10 having perforations 11 therein, said perforations being adapted to align with the vertical passage 12 passing through the fuel 13 in each container. In the disclosure in Figure 1 the container 2 is disclosed as being a water gas making container while the container 1 has just received a supply of fresh carbonaceous fuel. The fresh carbonaceous fuel of this container is preferably an amalgamated substance of finely pulverized coal and oil of a consistency resembling that of mortar having the passage-ways 12 which have been formed therein for the use of mandrels or the like which provide apertures for the passages of gases introduced to said fuel from the container 2 in a manner which will hereinafter appear. As the volatiles are removed the mass cokes or fuses, but still largely retains the apertures 12 when coked.

Communicating with the bases 3 and 4 of the containers 1 and 2 is an air feeding pipe 15, the same having a branch 16 controlled by the valve 17 leading to the chamber 8 of the base 4 and a branch 18 controlled by the valve 19 leading to the chamber 8 of the base 3. By the proper manipulation of these valves air may be admitted to either one of the containers 1 or 2 depending upon which container is being used as a water gas generator, the air passing up through the fuel in a container, then downwardly therethrough and into one of the chambers 7 where it is discharged, in a manner which will later appear. A valve control connection 20 also leads from the base 3 to the base 4. Positioned adjacent the containers 1 and 2 is a superheater 21, a connection 22 leading thereto from the chamber 7 of the base 3 having a valve 23 for controlling the same while a connection 24 leads to the superheater from the chamber 7 of the base 4 and controlled by the valve 25. This superheater is of the usual and well known construction having an overlying stack 26 and the usual blow-off valve at the top thereof. The upper portion of the superheater by means of the pipe 27 leads to a separator 28 from which the gases pass from the pipe 29, to a main 30 communicating with any type of gas storage receiver. The bases 3 and 4 of the containers 1 and 2 also receive steam conveying pipes 31 and 32 respectively controlled by the valves 33 and 34. Steam is admitted to these pipes through the common steam feed pipe 35 and enters each base opposite the side the air is introduced by the air feed pipes 16 and

18. It will be observed that the steam enters the chamber 7 in each base while the air enters the chamber 8.

It is one of the salient objects of this invention to manufacture enriched water gas by utilizing the volatiles of the fuel employed for the purpose of enriching the gas thereby eliminating or materially reducing the quantity of oil heretofore used for carburetting the gas. 78

In accordance with this process I contemplate imparting to the water gas practically all of the gases or volatiles of the coal. As shown in the drawings, the container 1 has therein a supply of fresh carbonaceous fuel, 80 preferably an amalgamated substance as manufactured in accordance with my process disclosed by Patent No. 1,420,164, with the cord openings or passages 12 extending therethrough. The container 1, however, 85 has therein a coked residue, or in other words, the residue resulting from the ordinary fresh fuel that had been placed therein and from which fuel the volatiles have been removed by a previous operation when 90 said container was being employed to receive and carburet the water gas rather than as a water gas generator. However, in the operation of this illustration of my process air is admitted to the container 2 through 95 the pipe 16, the same entering the chamber 8 of the base of the container, passing upwardly therethrough into the container closure 7 and thence downwardly through said coke mass in the container into the chamber 100 7, discharging through the pipe 24 by the opening of the valve 25 into the superheater 21 from where the same passes out into the usual stack. During this air blow the valve 105 in the connection 20 is closed so that, of course, none of the air can pass into the container 1. This air blow will place the coke in the container 2 in an incandescent state and is then discontinued in the usual manner by the closure of the valve 17. Steam is 110 then admitted through the steam feeding pipe 32 by opening the valve 34, the same entering the chamber 7 of the base of the container 2, passing upwardly through the incandescent bed of coke, and then downwardly through said bed into the chamber 8. At this time the valve 25 is closed and the valve in the connection 20 opened causing the blue water gas to pass into the chamber 8 of the base 3 of the container 1 115 upwardly through the apertured bottom of the container and through the cord openings 12 therein which hot gas serves to gasify or vaporize the rich volatiles in the fresh fuel of the container, which volatiles materially enrich the blue water gas. The water gas passes upwardly through the fuel and then downwardly through the same into the chamber 7 of the base of container 3, discharging from said chamber through 120

the pipe 22 by reason of the opening of the valve 23 into the superheater 21 where the gases become fixed, then through the pipe 27 into a gas separator 28 and from there 5 through pipes 29 and 30 into a suitable receiver. After such a steam run a second air run is, of course, resorted to, whereupon the steam controlling valve 34, and the valve in the connection 20 are closed while the 10 valves 17 and 25 are opened. The air run just described is repeated until the bed of fuel in the container 2 becomes incandescent whereupon a second steam run is resorted to.

15 It will be clearly apparent that during the air run the heated air is discharged directly into the superheater to heat the same, and does not at any time come in contact with the fresh fuel in the container 1. It is only 20 the decomposed steam that is admitted to this container. The alternate air and steam runs are carried on until the bed of coke in the container 2 has been largely used, and until the volatile content of the charge 25 in the container 1 has been fully gasified, and a residue left in this chamber consisting of coke. At this period the coke in the container 2 is removed and a new supply of fresh fuel is introduced thereto having 30 formed therein the cord openings. The coke removed from the container 2 is useful for any desired purpose and may be employed wherever preferable. When this coke has been removed and a new supply of fresh 35 fuel introduced thereto the container 2 no longer acts as the water gas generator, but becomes a carbureting container, acting in the manner of the container 1 in the previous operation. When said container 2 has 40 been filled with its fresh fuel then the coke residue in the container 1 is heated by an air run due to the opening in the valve 19 in the air feed connection 18, the air entering the chamber 8 of the base of this container, 45 passing upwardly through the coked mass therein, thence downwardly into the chamber 7, out through the pipe 22 of the opening of the valve 23, and into the superheater 1 from where it is discharged. During this 50 operation the valve in the connection 20 is, of course, closed. When the coke reaches an incandescent state, then the air supply is discontinued, and the valve 23 is closed while the valve in the connection 20 is 55 opened. Steam is then admitted through the steam feed 31 by an opening of the valve 33, the same entering the chamber 7 of the base of container 3 passing upwardly 60 through the incandescent coke and thence downwardly through the same into the chamber 8, being, of course, decomposed and forming water gas by the action of the hot carbon. The water gas passes through the pipe 20 into the chamber 8 65 of the base 4 of container 2, up through

the mass of fresh fuel therein, the hot gas vaporizing or gasifying the volatiles thereof, and out through the chamber 7 of the base through the pipe 24 in which the valve 25 has been opened, and into the 70 superheater 21 from where it is discharged in the usual manner. These runs are, of course, continued until the volatiles of the fresh fuel in the container 2 have been gasified. 75

In the apparatus disclosing a means for carrying out this process I have only shown two containers in series, but it will be understood that any number of containers may be employed, and that said containers may 80 be movably mounted if desired, so as to be progressively moved from carbureting zones to water gas making zones. The essential feature of this invention in all instances resides in a process by which the water gas is 85 enriched from volatiles removed from the fuel used in manufacturing such gas and it is intended that the accompanying claims be construed to broadly cover a process for accomplishing this end. The containers may 90 vary in capacity and as an illustration I may use a container having from 150 to 300 pounds of fresh fuel. The temperature of the coke in a water gas making container may also vary, but usually after an air blow 95 a temperature of 1400° F., is attained. The water gas imparts a temperature to the fresh fuel in a succeeding container acting as a carburetor which may vary from substantially above atmospheric to 1400° F., as the 100 operations proceed.

Having thus described my invention, what I claim is:

1. The process of producing an enriched water gas comprising successively admitting steam and air to a water gas making container having a charge of coke therein, formed with a plurality of open-ended vertical flues extending therethrough, in discharging the heated blast gases during an air blow to a superheater, in passing the water gas produced during a gas making period in the container to a second container having a fuel charge formed with a plurality of vertical flues extending therethrough, said charge containing volatiles to be removed by said water gas to enrich the same, in passing the enriched gas through the superheater, and in then collecting the same. 105
2. The process of producing enriched water gas, comprising alternately admitting steam and air to a water gas making container having a charge of coke therein, in passing the decomposed steam from said container during a gas making period through a fuel charge formed with a plurality of vertical flues extending therethrough, said charge having volatiles and disposed within a second container to enrich the water gas, and in employing the residue 110
- 115
- 120
- 125
- 130

in said second container after the removal of the volatiles for the production of water gas by introducing alternate supplies of air and steam thereto, and in enriching the gas thus produced by passage through a new fuel charge replacing the discharged coke in a previous gas making container.

3. The process of producing water gas, comprising alternately admitting air and steam to a water gas making container having a charge of coke therein formed with a plurality of vertical flues extending therethrough, in passing the water gas produced from said charge during a gas making period through a charge of fresh fuel in a second container to vaporize volatiles therein to enrich the water gas, said charge being of a plastic consistency and having a plurality of vertical passageways extending therethrough, in continuing the alternate air and steam runs through said first mentioned container, and the passage of water gas through the second container until the volatiles have been largely removed from the fuel charge in the second container, in then discharging the residue from the first mentioned container, and in introducing air and steam to said carbonized residue in said second container, and in passing the water gas produced therein through a fresh fuel charge in said first mentioned container.

4. The process of manufacturing water gas, comprising alternately introducing air and steam to a container having a charge of coke therein provided with open-ended vertical flues extending therethrough, in passing the heated blast gases during an air run therethrough into a superheater and then discharging the same, in passing water gas produced during a steam run through a sec-

ond container having a bonded fuel charge of fine carbonaceous fuel and oil, said mass being formed with a plurality of vertical passageways through which said water gas passes to vaporize the volatiles in the mass to enrich the water gas and in discharging the enriched water gas to the superheater, and in then collecting the same.

5. The process of manufacturing water gas, comprising alternately introducing air and steam to a container having a charge of coke therein provided with a plurality of separated open-ended passageways through which said air and steam pass, in introducing heated blast gases from said container during an air run therethrough into a superheater and then discharging the same, in passing water gas produced during a steam run through a second container having a bonded mass of fuel therein consisting of finely pulverized coal and oil provided with a plurality of formed passageways therein, through which passageways said water gas passes to vaporize the volatiles in said mass in discharging the enriched water gas to the superheater, and in then collecting the same, in continuing the alternate air and gas runs through a given container until the fuel therein has been largely consumed and the fuel in the carburettin container robbed of its volatiles, in thereafter discharging the residue from the water gas making container as coke, in alternately introducing air and steam to said container previously acting as a carburetor, and in passing the water gas thus produced therein through a new charge of fuel.

In testimony whereof I affix my signature.

WALTER EDWIN TRENT.
